UNITED STATES PATENT OFFICE.

ARTHUR C. GRIEWANK, OF OAKLAND, CALIFORNIA.

CONCRETE RAILWAY CAR.

Application filed October 31, 1918. Serial No. 260,434.

The object of the present invention is to provide a novel construction of car body, especially for railway cars and more particularly for freight cars, which, while made 5 of material much cheaper than those at present used, will be able to withstand the shocks, strains and stresses to which such car bodies are ordinarily subjected.

In the accompanying drawing, Figure 1 is 10 a side view of a reinforced concrete freight car constructed in accordance with my invention; Figure 2 is a transverse sectional view of the same on the line 2—2 of Figure 1; Figures 3, 4, 5, are similar views of modified forms of the car; Figure 6 is a partial longitudinal section of the same on the line 6—6 of Figure 2; Figure 7 is an end view thereof; Figure 8 is an enlarged broken side view of a portion of the car; Figure 9 is a 20 partial cross-sectional view thereof, also enlarged on the line 9—9 of Figure 8; Figure 10 is a similar view taken on the line 10—10 of Figure 8; Figure 11 is a broken plan view of a portion of the car; Figure 12 is a vertical section of a portion of a flat car showing a girder and floor and reinforcement therein; Figure 13 is a detail vertical sectional view showing the protectors for the flat car stake sockets; Figure 14 is an enlarged vertical longitudinal section of a portion of a car showing a girder in side elevation; Figure 15 is a horizontal sectional view on the line 15—15 of Figure 14, of one half of an end portion of the car; Figure 16 is a partial 30 vertical cross-section of said end on the line 16—16 of Figure 14; Figure 17 is a partial vertical cross-section of the car on the line 17—17 of Figure 14; Figure 18 is an elevation of an end beam, showing its free board and chafing iron for the coupler; Figure 19 is a horizontal section through an end of the car showing in detail the draft rigging; Figure 20 is a vertical section of the same on the line 20—20 of Figure 19; Figure 21 is a 40 enlarged vertical section on the line 21—21 of Figure 16; Figure 22 is a vertical section on the line 22—22 of Figure 21; and Figure 23 is a cross section on the line 23—23 of Figure 22.

50 Referring to the drawing, 1 indicates metallic car trucks of ordinary construction, in a socket in each of which, as in the ordinary railroad car, is received a king pin 2 secured to a center plate 3 (Fig. 14) on the truck. Said center plate is fastened to the under side of a concrete body bolster 6, ex-

tending transversely relative to concrete girders 7, and formed integral with said girders, as shown in Figure 15, said girders and bolster having at their common center a 60 vertically extending iron pipe 8 to receive the king pin 2.

The top of each girder 7 is approximately horizontal and level with necessary camber, but the girder is of greater depth in its middle portion than at the end portions, which are connected with the bolsters, and are supported by the trucks. In like manner the bolsters are preferably of greater depth or thickness at the central portions than at the end portions, in the case that, as shown in Figures 2, 5, girders are located only below the central portion of the floor, but where, as shown in Figures 3, 4, girders depend from the marginal portions of the floor, said bolsters are of uniform depth or thickness. Both the girder, or girders, if more than one are used, and the bolsters are preferably hollow, as shown in Figures 2, 3, 4, 6, 16, 17, although, as shown in Figure 5 they may be solid. As shown in Figures 6, 14, the body bolsters have preferably two cavities 9, extending horizontally therein. The concrete girder or girders and bolsters are formed in one piece not only with each other but with the floor 11, sides 12 and ends 13 of the car (however the walls, floor and ends may be made of concrete, steel, wood or any other suitable material), said sides and ends being preferably of panel-shaped form in order to 70 reduce the weight in proportion to the strength. The thicker portions 14 of the sides and ends act as posts. The floor is also strengthened by cross beams 16 integral therewith and which are also preferably 75 hollow, as clearly shown in Figures 6, 14.

The cavities in the beams 16 and in other parts of the apparatus which are hereinafter mentioned as being hollow may be made in any manner, as by casting the concrete 80 around hollow forms of the shapes of the cavities and made of pasteboard or other light sheet material, and which are secured in proper place in the main forms by means of very thin wires or rods, or by rods with 85 pipe sleeves around the rods and spacing the main and inner forms.

Where a girder or other element is mentioned in the claims as being hollow, it is 90 understood that the cavity in the girder or other element is closed. This construction gives great lightness as well as strength.

The concrete structure is reinforced throughout. The reinforcement consists partly of a series of steel rods 17, 18, which extend longitudinally at substantially uniform intervals in the floor and sides of the car respectively, and two series of oblique steel rods 19, 21, which cross each other at right angles and at an angle of 45° with the rods 17, 18, both of the series of rods 19, 21, 10 extending from the floor into the side walls.

In the under side of the floor of the car at its ends are formed recesses 43 extending at the ends of the car between the girders 7, shown in Figure 2. In said recess are contained three longitudinally extending horizontal helical springs 44 (Fig. 19). In the center of each spring extends an eye-bolt 46, the eye of said bolt surrounding a vertically extending bolt 47 surrounded by upper and 20 lower pipes 48 embedded in a concrete outward extension 49 of the adjacent bolster 6, the lower ends of said bolts having cotter pins 51, therethrough, the heads of said bolts preventing them from falling down. The 25 inner ends of said springs press against a vertical member 52 of an angular plate 53 (Fig. 20) which member in turn presses against a sheet 54 of shock-absorbing material, which in turn is pressed against the 30 outer surface of the concrete extension at the inner end of said recess. The outer ends of said springs 44 press against the inner surface of a rocker 56, which is held by nuts 57 on the outer ends of said eye bolts 46, which latter extend through holes 58 in said rocker. The 35 central portion of the outer side of said rocker is curved convexly and bears against a vertically extending portion of a U-shaped bridle plate 59, which is connected by bolts 61 and nuts 62 to said angular plate 53, the heads of said bolts 61 being curved convexly on the surfaces adjacent to said plate 53 to rock thereon, the sheet 54 having holes 63 to receive said heads. The bridle plate 59 is 40 connected by vertical bolts 64 to the inner end of a coupler 66, which extends through a comparatively narrow opening 67 in the front end of the concrete body of the car. A transversely extending retaining plate 68 is 45 secured to the horizontal member of the angular plate 53. Side chafing plates 71 receive the impact of the ends of the rocker. A chafing and supporting channel-iron 69 is secured to the plates 71 and closes the opening beneath the springs between the horizontal member of the angular plate 53 and the rocker 56.

The body bolster 6 is supported at eccentric portions thereof upon the top truck bolster by side bearings, best shown in Figures 21, 22, 23. Upon the truck bolster is secured a plate 72 upon which a lower cylindrical spring casing 73 can roll by means of rollers 74 having bearings in plates 76 depending from opposite sides of said casing.

Said spring casing 73 is received within an upper spring casing 77 embedded in the concrete of the body bolster, and within said spring casings 73, 77, is received a vertically extending helical spring 78, the ends of which press against the spring casings. Said spring casings are formed with central inward extensions 79 to prevent the spring from being displaced.

All rods are fastened together, either by welding or otherwise at points where they cross each other. The concrete girders 7 are reinforced by upper and lower series of bars 23, 24, the bars of the two series being connected by stirrups 26, as best shown in Figures 8, 9, 10, 14, 16, 17. Cross beams 16 and bolsters 6 are reinforced by upper and lower series of bars 27, 28, 29, 31, respectively which are connected by stirrups 32, 33, respectively. The thickened or post-like portions 14 of the sides of the car are immediately over the ends of the cross beams and the reinforcement of the cross beams is extended to said post-like portions by the lower bars 28 being extended upwardly, as clearly shown in Figure 9, in the inner portion of said post, and the upper bars 27, being extended upwardly in the outer portion of said post.

Said girders 7 are also reinforced by intermediate longitudinally extending bars 33 connected, as by wiring or other method of fastening, to the stirrups. As shown at 34, in holes 36 are placed anchors for fastening longitudinally extending metallic wearing plates 37 resting upon the concrete sides and forming protectors for the tops of said sides.

In the form of the invention shown in Figures 12, 13, which show a construction for a flat car, angular wearing plates 41 are used, and since the marginal portions of said flat cars have to be provided with sockets to receive the lower portions of uprights for the stakes or iron rods which are used on flat cars, these holes are protected by tubular iron protectors 42. The top of the floor and the inside of the vertical sides may be protected by sheet metal or by a concrete hardener.

I claim:

1. A car having metallic running gear and a concrete body thereon, said body comprising sides, floor, and supporting frame all integral with each other.
2. A car having metallic running gear and a concrete body thereon, said body comprising sides, floor, and supporting frame all integral with each other having metallic reinforcements, continuously extending between two of said portions of the body.
3. A car body having a girder extending longitudinally beneath said car body and integral therewith, said body and girder being formed of reinforced concrete.
4. A car body having girder extending

longitudinally beneath said car body and integral therewith, said body and girders being formed of reinforced concrete.

5. A car body having a longitudinally extending hollow girder integral therewith, said body and girder being formed of reinforced concrete.

6. A car body having longitudinally extending hollow girders integral therewith, said body and girder being formed of reinforced concrete.

7. A concrete car body having a bolster formed integral therewith.

8. A reinforced concrete body having a bolster formed integral therewith.

9. A reinforced concrete car body having a hollow bolster formed integral therewith.

10. A concrete car body having a girder and bolster formed integral therewith.

20 11. A concrete railway car having a bolster, girders, a floor, and cross beams connecting the bolster with the floor through the girders, all of said elements being integral with each other.

25 12. A concrete railway car having a bolster, girders, a floor, and hollow cross beams connecting the bolster with the floor through the girders, all of said elements being integral with each other.

30 13. A reinforced concrete car formed integral with a bolster therefor, said bolster having a plurality of longitudinally extending cavities therein.

35 14. A car body formed of concrete having therein reinforcing bars in three series, one extending longitudinally of the car and two extending obliquely thereto symmetrically with regard to the longitudinally extending bars.

40 15. A car body formed of concrete having therein reinforcing bars in three series, one extending longitudinally of the car and two extending obliquely thereto symmetrically with regard to the longitudinally extending bars, the parts of said reinforcing bars nearest to each other being secured together.

45 16. A car body having a floor and sides and formed of concrete and having two series

of bars extending obliquely in the floor of the car and extending into the respective sides 50 thereof.

17. A car body having a floor and sides and formed of concrete and having two series of bars extending obliquely in the floor of the car and extended into the respective 55 sides thereof and secured together at their points which are nearest to each other.

18. A car body construction comprising a frame consisting of longitudinal sills and transverse bolsters of reinforced concrete, 60 and a floor carried by said frame, said floor also being constructed of reinforced concrete.

19. A concrete car, comprising sides of concrete and a metallic wearing member on the upper edge of said walls and secured 65 thereto.

20. A concrete car having a metallic wearing member secured on its free edges.

21. A concrete railway car with walls and floor, and, thereunder, cross beams projecting beyond the edges of the floor and on the outside of said walls and integral with said cross beams, vertical posts; and on the top of said posts and walls, a longitudinal beam, all of the above parts being of concrete and 75 all adjoining parts integral with each other.

22. A concrete car with longitudinal girder of variable cross-section.

23. In combination with a concrete body of a car, a concrete underframe with a girder 80 with an enlarged portion at the bottom of same.

24. In a railway car a concrete body with concrete ends with posts stiffening said ends.

25. A car comprising a selfsustaining reinforced concrete body portion mounted on trucks, a hollow central longitudinal girder under said body portion and draw bar connections to said central longitudinal girder and means for connecting the car body to 90 the trucks.

26. A car with a reinforced concrete body with cross beams of concrete and a hollow girder and hollow bolsters.

ARTHUR C. GRIEWANK.
